a corporation of Pennsylvania

Application November 7, 1945, Serial No. 627,203

10 Claims. (Cl. 214—53)

1

This invention relates to material unloading apparatus and more particularly to a rotary car dump having associated therewith improved means for imparting hammer blows to the bottom of an inverted mine car to discharge any wet and sticky coal or similar material which might be solidly packed in the bottom of the car.

In the transportation of coal or similar material in mines, the loose coal is usually transported from the mine by a train of mine cars hauled by a mine locomotive and when the train of cars reaches the mine tipple, the coal is oftentimes dumped from the cars by a rotary dump which inverts a loaded car so that the loose coal is discharged therefrom by gravity. When a mine car is inverted in the rotary dump to discharge its contents, some difficulty has been encountered in completely discharging the wet and sticky coal which is solidly packed in the bottom of the car. In order to discharge the packed, wet and sticky coal from the car bottom it has been found necessary to hammer on the bottom of the inverted car in the rotary dump and, in known instances, hammering on the car bottom has been effected by means of pneumatic hammering tools which were mounted off at one side of the rotary dump and which were lowered into operative relation to the car bottom when the car is inverted in the dump.

The present invention is an improvement over previous known means for hammering on the bottoms of the inverted mine cars in the dump in that the hammering tools are mounted within the rotary dump itself so that when the dump is rotated to invert a mine car, the hammering tools move automatically into operative relation to the car bottom; and when the dump is rotated to turn the car right side up, the hammering tools move automatically into their inactive position out of contact with the car. In a preferred embodiment, the hammering tools are mounted in guides on the rotary dump for movement into and out of their operative hammering position with respect to the car bottom and the tools are supplied with pressure fluid through a common pipe connection extending longitudinally within the rotary dump and having a releasable fluid coupling for connecting the fluid supply on the dump to an extraneous source of pressure fluid.

It is accordingly an object of the present invention to provide a rotary car dump having associated therewith improved means for hammering on the bottom of an inverted mine car in the dump to release any wet and sticky material which might be solidly packed in the bottom

2

of the car. Another object is to provide an improved hammering mechanism which is mounted within the rotary car dump itself and which moves automatically into and out of its effective position with respect to the bottom of a mine car in the dump as the dump is rotated into its different positions. A further object is to provide an improved means for mounting a hammering tool on the rotary car dump. Still another object is to provide improved fluid supply connections for the hammering tools on the rotary car dump. These and other objects and advantages of the invention will, however, hereinafter more fully appear.

15 In the accompanying drawings there is shown for purposes of illustration one form which the invention may assume in practice.

In these drawings:

Fig. 1 is a side elevational view, with portions 20 in central longitudinal vertical section, of a rotary car dump with which an illustrative form of the invention is associated, and showing a mine car in inverted position in the dump.

Fig. 2 is a cross-sectional view taken substantially on line 2—2 of Fig. 1, showing the mine car in right side up position in the dump and with the fluid coupling released.

Fig. 3 is a view similar to Fig. 2, showing the mine car in inverted position and with the fluid 30 coupling connected.

Fig. 4 is an enlarged vertical sectional view taken substantially on line 4—4 of Fig. 1, showing one of the hammering tools in its operative hammering position.

35 Fig. 5 is a sectional view similar to Fig. 4, with the hammering tool in its inoperative inverted position.

Fig. 6 is a cross-sectional view taken substantially on line 6—6 of Fig. 4.

40 In this illustrative form of the invention the improved hammering means generally designated 1 is associated with a rotary car dump generally designated 2. Evidently, the invention may be associated with other types of material unloading apparatus.

The rotary car dump 2 is of a conventional design and includes a rotary car supporting structure or carrier 3 having circular end bearing-engagement supports 4, 4 mounted on bottom rollers 5 carried by a suitable base 6. The rotary dump structure or carrier 3 includes longitudinal frame members 7 and 8 secured to transverse frame members 9 within the circular end supports 4 and cross supports 10 secured to the members 7 along the length thereof, thus

providing a rigid rotary structure capable of supporting the weight of a loaded car such as a conventional mine car 11 such as is used in coal mines. Arranged longitudinally within the rotary carrier and secured to the cross supports 10 are track rails 12 which, when the rotary dump is in the position shown in Fig. 2, are aligned with the rails 13 and 14 (see Fig. 1) of a trackway leading to and from the rotary dump. The track rails 13, 14 may be laid on a suitable bed structure 15 laid on the floor or ground, or, if desired, the track bed may be supported directly on the floor or ground with the lower portion of the rotary dump arranged in a suitable recess such as a pit, in a well-known manner. Secured to the inner sides of the transverse frame members 9 and intermediate frame members 16 secured to the longitudinal frame members 7 and 8, are side flanges or ledges 17 which are received in longitudinal guideways 18 on the sides of the mine car 11 when the latter is moved within the rotary dump, and these side flanges serve to support the mine car when the latter is in inverted position as shown in Figs. 1 and 3. The mine car has a body 19 providing a receptacle for receiving the loose coal or other material to be transported, and the body is supported by wheels 20 adapted to travel along the track rails 13, 14 of the trackway leading to and from the rotary dump and along the track rails 12 within the rotary dump. Mounted on a suitable platform 21 off at one side of the rotary dump is a motor 22 for driving through a conventional clutch controlled transmission 23 a spur gear 24 which meshes with a large spur gear 25 on the outer periphery of one of the circular end supports 4 of the rotary dump. The transmission 23 embodies a conventional clutch mechanism operated by a hand lever 26 for connecting the gear 24 to the motor so that rotation of the dump may be started and stopped under manual control as desired. Evidently, suitable automatic stop mechanism may be provided for interrupting the drive when the rotary dump has turned through 180° into either of its opposite positions as shown in Figs. 2 and 3.

Now referring to the improved means for imparting hammer blows to the car bottom when a mine car is in inverted position on the carrier of the rotary dump, it will be noted that mounted on parallel supports 27, 27 secured to end plates 28 in turn secured to the cross supports 10 and the circular end supports 4, are hammering tools 29 extending radially with respect to the axis of rotation of the dump and which assume upright positions above the mine car, as shown in Figs. 1 and 3, when the mine car is inverted. There are shown herein three hammering tools spaced longitudinally of the rotary dump as shown in Fig. 1 although a greater or smaller number of tools may be employed under certain conditions. Each of these hammering tools comprises a tubular guide cylinder 30 preferably welded to side plates 31 which are secured by screws 32 to the parallel supports 27. Attached as by tie rods 33 to the ends of the cylinders are end plates 34 and 35, the latter having a central bore 36. Slidably guided in each of the guide cylinders 30 is a conventional fluid actuated hammer motor 37 comprising a motor cylinder 38 containing a reciprocating hammer piston 39 for delivering impact blows to a tappet 40 guided in a front cylinder head 41. The forward portion of the front cylinder head 41 is received in a bore 42 in a front cylindric guide block 43 which slid-

ingly fits the bore of the guide cylinder 30; and also arranged in the bore 42 of the front guide block is a bushing 44 which slidably receives and supports the shank 45 of a front striking bar 46. Arranged at the rear end of the motor cylinder is a rear cylindric guide block 47 also slidably received in the guide cylinder bore. The cylinder parts and the front and rear guide blocks are held in assembled relation as by tie bolts 48. The front striking bar 46 is received in the bore of the front guide block 43 and is held therein for limited axial movement by a pin and slot connection 49. The shank 45 of the striking bar projects rearwardly into the cylinder head 41 in position to receive the impact blows of the tappet 40, and the striking bar 46 projects forwardly through the bore 36 in the front head 35 of the guide cylinder 30 in position to strike blows on the plane surface 50 of a channel iron 51 rigidly secured to the bottom of the body 19 of the mine car 11. The hammer motor unit of each hammering tool is freely slidable longitudinally within the bore of the guide cylinder 30, and each guide cylinder is slotted longitudinally at 52 along one side thereof. Fluid under pressure may be supplied to the hammer motors of the several hammering tools from a common supply pipe 53 extending longitudinally of and supported within the rotary dump, through branch supply pipes 54 which pass through the guide cylinder slots 52 into connection with the conventional automatic fluid distributing means of the hammer motors. The fluid distributing means, as is well known to those skilled in the art, automatically distributes fluid through suitable ports and passages to the bore of the motor cylinder of each hammer motor under the control of a conventional fluid distributing valve mechanism to effect rapid reciprocation of the hammer piston whenever the pressure fluid supply is turned on. Since the specific structure of the fluid distributing means does not per se enter into the present invention, further disclosure thereof herein is unnecessary.

As previously mentioned, the branch supply pipes 54 for the pressure fluid are connected to the common supply pipe 53 within the rotary dump and pressure fluid is conducted to this supply pipe through a supply hose 55 leading to an inner coupling element 56 supported on the rotary dump. Connectible to the inner coupling element is an outer coupling element 57 which is supported on an upright 58 mounted on the platform 21. Connected to the outer coupling element through a conduit 59 is a supply hose 60 in turn connected to a conventional manual control valve 61. When the valve 61 is turned into its open position, pressure fluid may be conducted from a supply line 62 leading to a suitable source of fluid supply, through the supply hose 62, conduit 59, outer coupling element 57, and, when the fluid coupling is connected, through the inner coupling element 56 and hose 55 to the supply pipe 53 and thence through the branch pipes 54 to the hammer motors of the hammering tools. When the rotary dump is in the position shown in Fig. 2 with the mine car in upright position, the fluid coupling 56, 57 is released and when the rotary dump is turned through 180° to invert the mine car, as shown in Fig. 3, the fluid coupling 56, 57 may be connected to supply pressure fluid to the hammering tools. The fluid coupling structure is the invention of one Walter D. Fish and is fully described in a copending application Serial No. 627,202, filed Nov. 7, 1945.

The general mode of operation of the improved rotary car dump will be clearly apparent from the description given. When the rotary dump is in the position shown in Fig. 2, a loaded mine car 11 may travel along the trackway 13 leading to the rotary dump and along the track rails 12 in the dump and as the mine car moves along the rails 12 onto the rotary dump, the side flanges 17 are received in the guideways 18 on the mine car. The operator may then start the motor 22 and manipulate the lever 26 to effect rotation of the dump through the gearing 24, 25 from the position shown in Fig. 2 through 180° to the position shown in Figs. 1 and 3 wherein the mine car is inverted to discharge its contents, and the gearing 24, 25 may then be disconnected from the motor in any suitable manner either manually or automatically. As the rotary dump turns from the position shown in Fig. 2 to the position shown in Fig. 3, the hammering motors 37 of the hammering tools 29 slide inwardly along their guides 30 from the inverted inactive position shown in Fig. 5 to the operative position shown in Fig. 4, with the striking bar 46 in engagement with the surface 50 at the bottom of the mine car. The outer coupling element 57 of the fluid coupling may then be connected to the inner coupling element 56 on the rotary dump and the valve 61 may then be opened to supply pressure fluid past the fluid coupling through the hose 55, pipe 53 and branch pipes 54 to the hammering motors of the hammering tools to effect hammering on the car bottom, thereby to release the wet and sticky coal or other material which may be packed in the car bottom. When the inverted mine car is completely unloaded, the operator may release the fluid coupling 56, 57 and manipulate the lever 26 to effect rotation of the dump from the position shown in Fig. 3 through 180° back to its position shown in Fig. 2 to turn the car right side up and the unloaded mine car may then be moved along the track rails 12 from the rotary dump onto the trackway 14 leading from the dump. It will be evident that when the mine car is in its inverted position as shown in Figs. 1 and 3, the car is supported by the side flanges 17.

As a result of this invention, it will be noted that a rotary car dump is provided having associated therewith improved means for hammering on the bottom of an inverted mine car in the dump to release any wet and sticky coal or other material which might be solidly packed in the car bottom. It will be further evident that by mounting the hammering tools within the rotary dump itself, the hammering tools move automatically into operative relation with respect to the car bottom when the dump is rotated to invert a mine car and when the dump is rotated to turn the empty mine car right side up, the hammering tools move automatically into their inactive position out of contact with the car. The fluid supply connections arranged on the rotary dump in the manner disclosed provide extremely simple fluid supply means for the hammering tools. Other uses and advantages of the invention will be clearly apparent to those skilled in the art.

While there is in this application specifically described one form which the invention may assume in practice, it will be understood that this form of the same is shown for purposes of illustration, and that the invention may be modified and embodied in various other forms without departing from its spirit or the scope of the appended claims.

What we claim as new and desire to secure by Letters Patent is:

1. In a material unloading apparatus, in combination, a rotary car dump having car supporting means thereon for receiving a loaded mine car and supported for rotation between positions in which a car thereon is respectively upright and in an inverted discharging position, a hammering mechanism, and mounting means on said rotary dump for said hammering mechanism for supporting the latter for movement relative to said dump, said mounting means mounted on said rotary dump in such a position that the hammering mechanism moves toward the car when the latter is in discharging position on said dump and away from a car when the latter is upright, said hammering mechanism being supported on said mounting means with its hammering end towards a mine car supported on said dump and having a range of movement on said mounting means enabling its establishment of hammering relation with the car when the latter is in inverted discharging position.
2. In a material unloading apparatus, in combination, a rotary dump having car supporting means thereon for receiving a loaded mine car and supported for rotation between positions in which a car thereon is respectively upright and in an inverted discharging position, a fluid operated hammering mechanism, mounting means on said rotary dump for said hammering mechanism for supporting the latter for movement relative to said dump, said mounting means mounted on said rotary dump in such a position that the hammering mechanism moves toward the car when the latter is in discharging position on said dump and away from a car when the latter is upright, said hammering mechanism being supported on said mounting means with its hammering end towards a mine car supported on said dump and having a range of movement on said mounting means enabling its establishment of hammering relation with the car when the latter is in inverted discharging position, and fluid conducting means on said rotary dump for supplying operating fluid to said hammering mechanism and adapted for connection with an extraneous source of fluid supply.
3. In a material unloading apparatus, in combination, a rotary car dump having car supporting means thereon for receiving a loaded mine car and supported for rotation between positions in which a car thereon is respectively upright and in an inverted discharging position, a hammering mechanism, and guiding means on said rotary car dump for said hammering mechanism supporting the latter for free sliding movement, said guiding means mounted on said rotary car dump in such a position that the hammering mechanism slides towards a car when the latter is in discharging position on said dump and away from a car when the latter is upright, said hammering mechanism being supported on said guiding means with its hammering end towards a mine car supported on the car dump and having a range of sliding movement on said guiding means enabling its establishment of hammering relation with the car when the latter is in inverted discharging position.
4. In a material unloading apparatus, in combination, a rotary car dump having car supporting means thereon for receiving a loaded mine car and supported for rotation between positions in which a car thereon is respectively upright and in an inverted discharging position, a ham-

hammering mechanism, and guiding means on said rotary car dump for said hammering mechanism supporting the latter for free sliding movement, said guiding means extending longitudinally at right angles to the axis of rotation of said dump in such manner that the hammering mechanism slides towards a car when the latter is in discharging position on said dump and away from a car when the latter is upright, said hammering mechanism being supported on said guiding means with its hammering end towards a mine car supported on the car dump and having a range of sliding movement on said guiding means enabling its establishment of hammering relation with the car when the latter is in inverted discharging position.

5. In a material unloading apparatus, the combination comprising a rotary car dump having a generally circular carrier frame mounted for rotation about a central longitudinal axis and having car supporting means thereon for receiving a loaded mine car, and rotatable about said axis between positions in which a car is respectively upright and in an inverted discharging position, a hammering device, and a cross guide on said carrier frame within the confines thereof and arranged longitudinally at right angles to the axis of rotation of said dump, said guide disposed on said frame at one side of said car supporting means in such a position that said hammering device moves along said guide towards a car when the latter is in discharging position on said dump and away from a car when the latter is upright, said hammering device being supported on said guide with its hammering end towards a mine car supported on the car dump and having a range of movement on said guide enabling its establishment of hammering relation with the car bottom when the car is in inverted discharging position.

6. In a material unloading apparatus, the combination comprising a rotary car dump having a generally circular carrier frame mounted for rotation about a central longitudinal axis and having car supporting means thereon for receiving a loaded mine car and rotatable about said axis between positions in which a car is respectively upright and in an inverted discharging position, a fluid operated hammering motor, a cross guide on said carrier frame within the confines thereof and arranged longitudinally at right angles to the axis of rotation of said dump, said guide disposed on said frame at one side of said car supporting means in such a position that said hammering motor moves along said guide towards a car when the latter is in discharging position on said dump and away from a car when the latter is upright, said hammering motor being supported on said guide with its hammering end towards a mine car supported on the car dump and having a range of movement on said guide enabling its establishment of hammering relation with the car bottom when the car is in inverted discharging position, and fluid conducting means on said carrier frame for conducting fluid to said hammering motor and adapted for connection to an extraneous source of fluid supply.

7. In a material unloading apparatus, the combination comprising a rotary car dump having a generally circular carrier frame mounted for rotation about a central longitudinal axis and having car supporting means thereon for receiving a loaded mine car and rotatable about said axis between positions in which a car is respectively upright and in an inverted discharging position, a

fluid operated hammering motor, a cross guide on said carrier frame within the confines thereof and arranged longitudinally at right angles to the axis of rotation of said dump, said guide disposed on said frame at one side of said car supporting means in such a position that said hammering motor moves along said guide towards a car when the latter is in discharging position on said dump and away from a car when the latter is upright, said hammering motor being supported on said guide with its hammering end towards a mine car supported on the car dump and having a range of movement on said guide enabling its establishment of hammering relation with the car bottom when the car is in inverted discharging position, fluid conducting means on said carrier frame for conducting fluid to said hammering motor and adapted for connection to an extraneous source of fluid supply, and control means mounted extraneously to said rotary carrier frame for controlling fluid flow from said source to said fluid conducting means for effecting starting and stopping of said motor.

8. In a material unloading apparatus, the combination comprising a rotary car dump mounted for rotation about a central longitudinal axis and having car supporting means including a trackway at one side of said axis on which a loaded mine car is adapted to be supported, said car supporting means being supported for rotation with said dump between positions in which a car thereon is respectively upright and in an inverted discharging position, a hammering device, and guiding means mounted on said rotary dump at the same side of said axis as said trackway for supporting said hammering device for guided movement relative to said dump, said guiding means so disposed on said dump that the hammering device moves therealong towards a car when the latter is in discharging position on said dump and away from a car when the latter is upright, said hammering device being supported on said guiding means with its hammering end towards a mine car supported on the car dump and having a range of movement along said guiding means enabling its establishment of hammering relation with the car bottom when the car is in inverted discharging position.

9. In a material unloading apparatus, the combination comprising a rotary dumping means having a generally circular carrier frame mounted for rotation about a central longitudinal axis and supporting means thereon for receiving a loaded receptacle, said carrier frame supported for rotation between positions wherein a receptacle thereon is respectively upright and in inverted discharging position, power operated hammering means, and means for mounting said hammering means within the confines of said carrier frame for movement relative thereto, said mounting means mounted on said carrier frame in such a position that said hammering means moves toward the receptacle when the latter is in discharging position and away from the receptacle when the latter is upright, said hammering means being supported on said mounting means with its hammering end towards a receptacle supported on the dumping means and having a range of movement on said mounting means enabling its establishment of hammering relation with the receptacle bottom when the receptacle is in inverted discharging position.

10. In a material unloading apparatus, the combination comprising a rotary car dump having a circular carrier frame including annular end

frame members and supported for rotation about a central longitudinal axis, said carrier frame having car supporting means thereon for receiving a loaded mine car and being rotatable about said axis between positions in which a car thereon is respectively upright and in inverted discharging position, a plurality of fluid operated hammers, guides on said carrier frame for supporting said hammers for free movement therealong and extending longitudinally at right angles to said axis of rotation of said carrier frame and equally spaced longitudinally of said frame, said guides mounted on said carrier frame in such positions that the hammers move therealong towards a car when the latter is in discharging position and away from a car when the latter is upright, said hammers being supported by said guides with their hammering ends towards a mine car supported on the car dump and having a range of movement along said guides enabling their establishment of hammering relation with the car bottom when the car is in inverted discharging position, and fluid conducting means on said rotary carrier frame for supplying operating fluid to said hammers and adapted for connection to an extraneous source of fluid supply, said fluid conducting means in-

cluding a rigid fluid conduit extending longitudinally of said carrier frame and supported by said end frame members and flexible fluid conduits between said rigid conduit and each of said hammers.
